UNITED STATES PATENT OFFICE.

PATRICK J. HARRIGAN, OF MCKEESPORT, PENNSYLVANIA.

JOURNAL-BOX.

No. 856,059.

Specification of Letters Patent.

Patented June 4, 1907.

Application filed December 15, 1906. Serial No. 343,055.

To all whom it may concern:

Be it known that I, PATRICK J. HARRIGAN, a citizen of the United States of America, residing at McKeesport, in the county of Allegheny and State of Pennsylvania, have invented certain new and useful Improvements in Journal-Boxes, of which the following is a specification, reference being had therein to the accompanying drawing.

10 This invention relates to journal boxes, and has for its object to provide a device of this character so constructed as to direct the lubricant toward the inner end of the box, and also toward the axle revolvably mounted 15 therein.

Another object of this invention is to provide a journal box in which the volume of oil and waste at the back of the journal is increased to provide a more effective lubrication at that part of the axle journaled therein, which receives the greatest amount of wear.

To this end, I have devised a simple and inexpensive journal box that will prevent 25 any settling of the waste packing away from the journal, the box being easily and quickly packed with waste, thereby facilitating the work of the car inspector and oiler.

The construction of the improvement 30 will be fully described hereinafter in connection with the accompanying drawing, which forms a part of this specification, and then specifically pointed out in the appended claim.

35 In the drawing, Figure 1 is a horizontal section of the journal box on the line $x-x$ of Fig. 2, and Fig. 2 is a central vertical section of the journal box.

In the accompanying drawing, the reference numeral 1 designates a box having an inclined bottom 2 and having the inner ends 3 of its side walls outwardly inclined to provide ample space for waste and lubricant, said space having an inclined bottom and 45 sides as shown for the purpose above indicated of directing the lubricant and waste toward the inner end of the box. The rear end of the bottom 2 of the box is inclined up-

wardly as at 4, whereby when the waste and lubricant has a tendency to settle toward the rear end of the journal box, it will be forced 50 upwardly to engage the axle or spindle 5 journaled within the box. The box as illustrated is provided with the usual opening 5, whereby the interior of the box can be 55 inspected, and refilled with waste and lubricant at any desired time, also with the usual form of dust guard opening 6, together with brasses 7.

My invention entirely resides in the inclination of the bottom, sides and end of the box, and for this reason I do not care to confine myself to the type of dust guard used in connection with the journal box or to other features thereof.

A further important advantage of my improved construction of box is, that the natural tendency of the waste is to move toward the rear, and any tendency of the packed waste to move forward results in wedging 70 it against the under surface of the journal into the position where it best serves the purpose of lubrication. Again, in case of derailment, the downward movement of the journal within the box serves to force the 75 packed waste upward along the inclined sides of the box as well as rearward. Thus any jarring movement of the journal by my improvement results in forcing the waste to the rear and upward along the sides as above 80 stated.

What I claim and desire to secure by Letters Patent, is:—

A journal box having a bottom inclined from the front end to the rear end wall, and 85 having its side walls flaring outwardly from a point intermediate the ends to the rear end, and having a part of the rear wall inclined upwardly and rearwardly, as and for the purpose described.

In testimony whereof I affix my signature in the presence of two witnesses.

PATRICK J. HARRIGAN.
